UNITED STATES PATENT OFFICE

170,480

COMBINED FOOD WARMER AND BUN TOASTER

Irving Sacks, Brooklyn, N. Y.

Application November 19, 1952, Serial No. 22,367

Term of patent 14 years

(Cl. D81—10)

To all whom it may concern:

Be it known that I, Irving Sacks, a citizen of the United States of America, and a resident of New York city, Borough of Brooklyn, county of Kings and State of New York, have invented a new, original, and ornamental Design for a Combined Food Warmer and Bun Toaster, of which the following is a specification, reference being had to the accompanying drawing, forming a part hereof, in which—

Fig. 1 is a front view of a combined food warmer and bun toaster, showing my new design,

Fig. 2 is a top plan view,

Fig. 3 is a view of one end,
Fig. 4 is a view of the other end, and
Fig. 5 is a rear view thereof.

I claim:

The ornamental design for a combined food warmer and bun toaster, substantially as shown.

IRVING SACKS.
